UNITED STATES PATENT OFFICE.

ALBEN E. LUNDELL, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,254,712.

Specification of Letters Patent. Patented Jan. 29, 1918.

Application filed June 17, 1916. Serial No. 104,232.

To all whom it may concern:

Be it known that I, ALBEN E. LUNDELL, a citizen of the United States, residing at New York, in the county of Bronx and 5 State of New York, have invented certain new and useful Improvements in Telephone-Exchange Systems, of which the following is a full, clear, concise, and exact description.

10 This invention relates to telephone exchange systems, and more particularly to telephone exchanges in which the establishment of connections is controlled from an operator's position.

15 In telephone exchange systems in which there are provided a plurality of connecting or cord circuits at an operator's position to which an operator's telephone set is common, a plurality of switching devices are 20 provided for controlling the association of the operator's telephone set with the connecting circuits. In such systems it may happen that the operator, after having actuated one of the switching devices for connecting her telephone to a connecting circuit, fails to release the switching device, and therefore, when another switching device is 25 actuated for connecting the telephone set to another connecting circuit, the operator will 30 be connected to two connecting circuits, and may extend the connecting circuit to which one party is connected to a line desired by the other party.

35 In order to prevent the occurrence of such undesired connections, it has been proposed to move one of the switching devices out of a listening-in position, while another switching device is moving from the normal to the 40 listening-in position. For the purpose of insuring the proper functioning of the system, a time interval has been provided between the normal and the listening-in positions of the switches. The disadvantage of 45 such arrangements is that the building up of connections is slowed down, and further, that due to inaccuracies in the adjustment of magnets or mechanisms, the proposed time interval will not prove sufficient.

50 It is the object of this invention to provide means for definitely controlling the co-operation of a plurality of switching devices such as sequence switches employed for the above defined purpose, whereby the occurrence of double connections is prevented 55 without the necessity of interposing time margins between the normal and listening-

in positions of the switches. Preferably a switch is moved out of its listening-in position while another switch is in a resting position and will, in turn, move this later 60 mentioned switch into the listening-in position.

In the drawings Figure 1 represents a calling and called subscriber's circuit and an operator's connecting circuit and apparatus; 65 and Fig. 2 an operator's controlling apparatus. Only so much is shown of the circuits and apparatus as is necessary for a clear understanding of this invention. A full disclosure of a system of the same general type 70 may be had from Patent No. 1,168,319, patented January 18, 1916, to A. E. Lundell.

A calling subscriber at substation 1, desiring to obtain a connection with a called subscriber at substation 2, removes his receiver from the switchhook, causing thereby the displaying of a well-known calling line signal. The operator inserts then her plug 3 into jack 4, closing thus a circuit from grounded battery through a resistance 5, the 80 sleeve contacts of jack 4 and plug 3, and the winding of a relay 6, to ground. Relay 6 closes a circuit from ground through its armature and front contact, a contact 7 and the power magnet of a sequence switch 8, to 85 grounded battery, and this sequence switch is moved out of its normal position 1 and under the control of a normal spring 9 into a resting position 2.

90 Sequence switch 8 controls the connection between the operator's telephone set 10 and a connecting circuit 11. Another sequence switch 12 controls the association of the operator's telephone head set 10 with another connecting circuit (not shown). Supposing 95 that the sequence switch 12 is in the listening-in position 4, and therefore a circuit is closed from ground through contact 13 of sequence switch 12, conductor 14, and the winding of a relay 15 common to the cord 100 circuits of the operator's position, to grounded battery. Relay 15 being energized, sequence switch 8 remains in position 2. A circuit is closed now from ground through contact 16 of sequence switch 8, conductor 17, a contact 18 and the power magnet of sequence switch 12, to grounded battery, and under the control of a normal spring 19, this sequence switch is moved out of position 4 105 into a listening-out position 11.

110 When sequence switch 12 leaves position 54, the circuit of the common relay 15 is

opened, this relay becomes deenergized and closes a circuit from ground through its armature and back contact, a contact 20 and the power magnet of sequence switch 8, to 5 grounded battery, for moving this sequence switch into the listening-in position 4, in which position the operator's telephone 10 is connected through sequence switch contacts 21 and 22, to the connecting circuit 10 11 and thus into telephonic association with the calling subscriber.

The operator having learned the number of the desired line, actuates her keyboard (not shown) in accordance with the numerical designation of this line, for adjusting a sender 25 adapted to control a train of automatic selector switches such as 26, 27 and 28.

When sequence switch 8 reached position 20 4, a circuit was closed from ground, through the armature and front contact of relay 6, sequence switch contact 30, the contact 31 and the power magnet of sequence switch 32 to grounded battery. Under the control 25 of a normal spring 23, sequence switch 32 is moved out of position 1 into position 11.

When sequence switch passes through position 2, a circuit is closed from ground through sequence switch contact 33, conductor 34, a wiper 35 of a well-known cord 30 finder 36 adapted to connect the operator's controlling apparatus with the selected connecting circuit, a contact 37 of sequence switch 40 and the winding of a relay 39 to 35 grounded battery. This relay becomes energized; and, by attracting its right-hand armature, closes a driving circuit for a sequence switch 40 through a sequence switch contact 41, for moving this sequence switch 40 out of position 1 into position 2. Relay 39 does not become deenergized when sequence switch 40 leaves its first position, a circuit being closed from grounded battery through the winding of this relay, sequence switch 45 contact 42, the left-hand contact and armature of relay 39, cord finder brush 43, conductor 44 and contact 45 of sequence switch 32 to ground.

The operator depresses now her start key 50 46, whereupon a circuit is closed from ground through the contact of key 46, and a contact 47 and the power magnet of sequence switch 40 to grounded battery, for moving this switch out of position 2 into 55 position 8. A circuit is then closed from ground through sequence switch contact 50, a contact 51 and the power magnet of sequence switch 38 to grounded battery, and this switch is moved out of position 1 into position 2.

In position 2 of sequence switch 38 and position 11 of sequence switch 32, the fundamental or controlling circuit is extended to selector switch 26, this circuit being traceable through sequence switch contact 55,

conductor 56, cord finder brush 57, the windings of a stepping relay 58, the left-hand contact and armature of a relay 59, sequence switch contact 60, cord finder brush 61, conductor 62 and sequence switch contact 63. 70 Under the control of revertive impulses sent from selector 26 to the stepping relay 58, the sender is caused in the well-known manner to be stepped toward its normal position. After the setting of selector switch 26 in 75 accordance with the first digit designated by sender 25, relay 59 becomes energized in the well-known manner and opens at its left-hand contact the fundamental circuit, causing thereby the arresting of selector 26 80 on the selected row of terminals, whereupon switch 26 automatically hunts for a free trunk in the selected group. Relay 59 closes also a driving circuit from ground through its right-hand armature and contact, a contact 64 and the power magnet of sequence switch 38 to grounded battery for moving this switch out of position 2 into position 4, whereupon relay 59 again becomes deenergized and reestablishes the fundamental circuit, which is now extended through the wipers of selector 26 to a trunk leading to another selector 27. Selector 27 and connector 28 are controlled in their setting operation in the same manner as was described 95 in connection with selector 26, with the exception that connector 28 is adjusted in accordance with two digits for selecting the line leading to substation 2. After the sending out of each digit, relay 59 is energized 100 and closes the above traced driving circuit for sequence switch 38, whereby, after the setting of connector 28, sequence switch 38 is moved out of position 8 into position 9. A circuit is then closed from ground through sequence switch contact 65, cord finder brush 66, conductor 67, a contact 68 and the power magnet of sequence switch 32 to 105 grounded battery, and this switch is moved out of position 11 into position 16. In position 16 of sequence switch 38, the talking circuit is established through sequence switch contacts 70 and 71, the called substation being signaled in any well-known manner.

When sequence switch 32 leaves its position 11, contact 45 is opened and therefore relay 39 becomes deenergized and closes a circuit from ground through its right-hand armature and back contact, a contact 72 and the power magnet of sequence switch 40 to 110 grounded battery, for moving the sequence switch out of position 8 into position 17. A circuit is now closed from ground through the right-hand armature and back contact of relay 39, sequence switch contact 73, conductor 74, a contact 75 and the power magnet of sequence switch 38 to grounded battery, whereupon sequence switch 38 is driven out of position 9 into its first position. When sequence switch 38 reaches position 1, 130

a circuit is closed from ground through the right-hand armature and back contact of relay 39, sequence switch contacts 73, 76, 78 and the power magnet of switch 40 to 5 grounded battery for driving it to position 1. The operator's sending and controlling apparatus being released to normal, it may be employed now for controlling the establishment of another connection.

10 After the operator has finished the conversation with the calling substation, she depresses a listening-out key 100, whereupon a circuit is closed from ground through the contact of this key 100, a contact 101 and the power magnet of sequence switch 8, to grounded battery, and this sequence switch is moved into a listening-out position 11, in which position the operator's telephone set 10 is disconnected from the connecting circuit. If for any reason the operator desires to listen in again, she depresses a listening-in key 102, closing thus a circuit from ground through the contact of this key, a contact 109 and the power magnet of sequence switch 8 to grounded battery, for moving this sequence switch into position 1, and relay 6 being energized, a circuit is closed through sequence switch contact 7 for sequence switch 8, for moving this switch into 25 position 2. Due to the deenergized condition of relay 15, the sequence switch moves into position 4.

When the parties have finished their conversation, the operator, by pulling out plug 35 3 from jack 4, causes the deenergization of relay 6, which in turn closes a circuit from ground through its armature and back contact, contact 103 and the power magnet of sequence switch 8 to grounded battery, causing the movement of sequence switch 8 out 40 of position 11 into position 1. When sequence switch 8 reaches position 1, a circuit is completed from ground through the armature and back contact of relay 6, sequence 45 switch contact 104, a contact 105 and the power magnet of sequence switch 32 to grounded battery. Due to the closure of this circuit, sequence switch 32 will be moved into position 1 and the switches 26, 27 and 50 28 employed in the connection are restored to normal in the well-known manner.

Should the operator fail to depress key 100 and employ sequence switch 12 for extending her telephone set to another connecting circuit, this sequence switch when moved out of position 1 into position 2 by a relay corresponding to relay 6, causes the closure of a circuit from ground through a contact 106, conductor 17, a contact 107 and the 60 power magnet of sequence switch 8 to grounded battery for moving this sequence switch out of position 4 into position 11,

from which position the sequence switch 8 is moved to position 1 by the above traced circuit extending from the back contact of 65 relay 6 through contact 103. Sequence switch 8 maintained relay 15 energized in positions 4 to 5₁ through a contact 108 which will now open the circuit of this relay, whereupon switch 12 is moved into position 70 4 in the same manner as above described in connection with sequence switch 8.

What is claimed is:

1. In a telephone exchange system, a plurality of lines, a plurality of connecting circuits by means of which said lines may be interconnected, an operator's telephone set, a switch for each of said connecting circuits adapted to associate said telephone set therewith, and means controlled by one switch 75 80 while at rest for actuating another switch.

2. In a telephone exchange system, a plurality of lines, a plurality of connecting circuits by means of which said lines may be interconnected, an operator's telephone set, 85 a switch for each connecting circuit adapted to associate said telephone set therewith and having a normal, a resting and a listening-in position, means operative upon the extension of a connecting circuit to a calling line for 90 moving the associated switch to its resting position, means controlled by said switch in its resting position for moving another switch which is in the listening-in position, and means controlled by said later mentioned switch for moving the first mentioned switch into the listening-in position. 95

3. In a telephone exchange system, a plurality of lines, a plurality of connecting circuits by means of which said lines may be 100 interconnected, an operator's telephone set, a switch for each of said connecting circuits for associating said telephone set therewith and having a resting and a listening-in position, and means controlled by any one of 105 said switches when moved into the resting position for actuating another switch which is in the listening-in position.

4. In a telephone exchange system, a plurality of lines, a plurality of connecting circuits for said lines, an operator's telephone set, a switch for each of said circuits for connecting said telephone set thereto and having a resting and a listening-in position, a relay, means for actuating said relay when any 110 115 of said switches is in the listening-in position, means controlled by one switch for moving another out of the listening-in position, and means controlled by said relay for moving any switch into the listening-in position. 120

In witness whereof, I hereunto subscribe my name this 15th day of June A. D., 1916.

ALBEN E. LUNDELL.
